Attest:

UNITED STATES PATENT OFFICE.

THOMAS G. COOPER, OF JARVIS, ONTARIO, ASSIGNOR OF ONE-TENTH TO
SAMUEL JOHN MOORE, OF TORONTO, CANADA.

BLACK-LEAF CHECK-BOOK.

SPECIFICATION forming part of Letters Patent No. 323,276, dated July 28, 1885.

Application filed July 7, 1884. (No model.) Patented in Canada September 6, 1884, No. 20,148.

To all whom it may concern:

Be it known that I, THOMAS GEORGE COOPER, of the village of Jarvis, in the county of Haldimand, in the Province of Ontario, Canada, gentleman, have invented certain new and useful Improvements in Black - Leaf Check-Books; and I do hereby declare that the following is a full, clear, and exact description of the same.

10 The invention relates to that class of black-leaf check-books in which several copies of the writing are taken simultaneously, a black leaf being inserted between each of the copying-leaves, and a metal plate placed below the last leaf to receive the copy in order to separate it from the balance of the leaves remaining in the book; and it consists in the peculiar combinations and the construction and arrangement of parts, hereinafter more fully described 15 and claimed.

Figure 1 is a perspective view of my improved black-leaf check-book, showing the copying-leaves, metal plate, and black leaves thrown back clear of the body of the book. Fig. 2 is a perspective view showing the metal plate placed in position and the first black leaf in the act of being placed. Fig. 3 is a perspective view showing the metal plate and black leaves in position, and the top leaf, which 20 has been written on, in the act of being raised.

The drawings represent a black-leaf check-book designed to receive two copies of the original writing; but of course the number may be greatly increased by simply increasing 25 the number of black leaves, and adding to the leaves on which the writing is transcribed.

A, B, and C are three leaves separated by perforated lines *a*, so that they can readily be detached, if necessary. The end of the leaf 30 A, it will be noticed, is attached to the back of the book, while the other leaves, B and C, are simply folded into the book, and form what might practically be termed "fly-leaves."

D is a zinc or other sheet-metal plate connected to the back of the book by a double joint or flexible hinge, E, the flexible hinge E being designed to allow the plate D to accommodate itself to the decreasing thickness of the book as the leaves are removed. I show 45 metal hinges in the drawings; but it will be

understood that leather or other flexible material might be used instead.

F and G are two black leaves connected to the same or opposite side to that on which the plate is hinged.

When the book is to be used for writing memoranda, the series of leaves A, B, and C to receive the memorandum are open, so as to permit the sheet-metal plate D to be placed between them and the leaves it is not intended 55 to copy on. The leaf A is then placed on top of the tin plate D, and the first black leaf, F, is thrown on top of it. Then the leaf B is folded back over the black leaf F, when the black leaf G is placed on top of B, and the leaf C on 60 top of it. On this latter leaf the memorandum is written, the black leaves G and F transmitting the writing onto the leaves B and A, while the plate D prevents the impression going any 65 farther. When the memorandum is finished, 70 the leaves C, B, and A may be thrown back into the position shown in Fig. 1, the black leaves F and G being thrown out during the operation. The leaves thus thrown out may be left connected to the book without interfering with writing a further memorandum on the other leaves below the plate D, the said latter leaves being simply taken out and manipulated in the same manner as A, B, and C. 75

Owing to the perforated lines *a*, the leaves 80 C and B can be detached and the leaf A allowed to remain in the book; or this latter leaf may also be torn out, if desired.

Although I think it preferable to attach the leaves A, B, and C together, so that they may 85 be manipulated as described, the advantage of the hinged plate D may be in a great measure secured in a book in which the leaves are separately bound into the book. In this arrangement a plate attached to the book so that it 90 will not draw out, and will at the same time accommodate itself to the decreasing thickness of the book, will be secured.

In another application filed by me July 24, 1884, Serial No. 138,605, I show and claim a 95 single black leaf held to the cover at right angles to the fold of the leaves; but in that construction the leaves have but one fold, and the fastening means are portable and independent of the book structure.

I do not claim anything new in the employment of a sheet-metal plate and a number of black leaves placed between the copying-leaves; but

What I do claim as my invention is—

1. The leaves A, B, and C, connected together, and having one of their ends fastened to the book, in combination with the black leaves F and G, fastened to the book at right angles to the fastening of the leaves, and the sheet-metal plate D, flexibly connected to the book at right angles to the connection of the leaves A, B, and C, substantially as described.

2. In a black-leaf check-book arranged to produce simultaneously several copies of a written memorandum, the leaves A, B, and C, connected to and folded in the book as de-

scribed, in combination with a metal plate, D, flexibly connected to the book at right angles to the connection of the leaves.

3. In combination with a black-leaf check-book, a metal plate, D, flexibly hinged to the cover by a double joint, whereby said plate will accommodate itself to the decreasing thickness of the book as the leaves are removed, substantially as and for the purpose specified.

Signed at the city of Toronto this 7th day of June, 1884.

THOS. G. COOPER.

In presence of—

CHARLES C. BALDWIN,
JAS. E. MAYBEE.
